X-RAY TUBE HOUSING

William K. Johnson, Oakbrook, and Paul V. Hartman,
Bellwood, Ill., assignors to Picker Corporation, White
Plains, N.Y.

Filed May 27, 1970, Ser. No. 23,173

Term of patent 14 years

Int. Cl. D24—02

U.S. Cl. D83—1

FIG. 1

FIG. 2

FIG. 6

FIG. 3

FIG. 4

FIG. 5

FIG. 1 is a perspective view of an X-ray tube housing showing our new design with the port side down and at 90 degrees from the horns;

FIG. 2 is a top plan view thereof with the port at zero degrees;

FIG. 3 is a side elevational view thereof with the port at 90 degrees;

FIGS. 4, 5 and 6 are end elevational views thereof showing the port at 90, 180 and zero degrees, respectively.

We claim:

The ornamental design for an X-ray tube housing, as shown and described.
